SWORD BLADE

Eric L. Cole, London, England, assignor to Wilkinson
Sword Limited, London, England

Filed June 16, 1970, Ser. No. 23,508

Term of patent 14 years

Int. Cl. D22—02

U.S. Cl. D22—1

FIG. 3.

FIG. 1.

FIG. 2.

FIG. 1 is a front elevational view of a sword blade showing my new design, the blade fragmentarily shown for convenience of illustration;

FIG. 2 is a front elevational view thereof showing that portion of the blade omitted in FIG. 1; and

FIG. 3 is a side elevational view thereof on a reduced scale.

The hilt and crossguard are shown in broken lines in FIGS. 1 and 3 for illustrative purposes only.

The rear of the blade is plain.

The characteristic feature of my design resides in the surface ornamentation of the blade.

I claim:

The ornamental design for a sword blade, as shown and described.
